UNITED STATES PATENT OFFICE.

FREDRICK A. SCHWARZROCK, OF MILWAUKEE, WISCONSIN.

SUITCASE.

1,093,484.

Specification of Letters Patent. Patented Apr. 14, 1914.

Application filed February 18, 1911. Serial No. 609,305.

To all whom it may concern:

Be it known that I, FREDRICK A. SCHWARZROCK, a citizen of the United States, residing at Milwaukee, in the county of Milwaukee 5 and State of Wisconsin, have invented new and useful Improvements in Suitcases, of which the following is a specification.

This invention relates to improvements in the construction of suit cases or the like, and 10 the primary object of the invention is to simplify and improve the existing art by producing an article of this character which shall be simple in construction, strong and durable, all of the members comprising the 15 same being easily and quickly connected together and which also contemplates a great saving of the materials employed in the construction.

With the above, and other objects in view, 20 which will appear as the description progresses, the invention resides in the novel construction and combination of parts hereinafter fully described and claimed.

In the accompanying drawings, Figure 1 25 is a perspective view of a case constructed in accordance with the present invention. Fig. 2 is a transverse sectional view of the same. Fig. 3 is a longitudinal sectional view of the same. Fig. 4 is a plan view of the parts 30 from which the top of the case is formed, portions of the overlapping sections being bent to disclose the underlying sections. Fig. 5 is a similar view of the top or closure 35 of the case.

35 In the drawings the numeral 1 designates the improved case, which, as illustrated in Fig. 1 of the drawings, is of a substantially rectangular formation and is provided with a hinged closure 2. The case is provided 40 with the usual handle and also with the usual locking members whereby the hinged closure is fastened to the body of the case.

The body of the case comprises a side 3, top 4, bottom 5 and ends 6. As illustrated 45 in Fig. 4 the side and top and bottom have their inner or body portion formed of a single piece of suitable material, such as heavy card-board, or the like, and which is designated by the numeral 7. The board 7 is sub- 50 stantially rectangular in shape and the portion forming the side 3 is divided from the portions forming the top 4 and the bottom 5 by the longitudinally extending scored lines designated by the numerals 8 and 9 respectively. The board 7 has its outer face en-

tirely coated with an adhesive material designated by the numeral 10, and the said adhesive is adapted to securely fasten to the board an outer facing 11. This facing is preferably constructed of fiber matting, as 60 shown in the drawings, but it is to be understood that I do not limit myself to this particular material, as any of numerous other materials may be substituted if desired. The facing 11 is cut substantially rectangular, 65 but is of a lesser size than the board 7 so that a space of perhaps a couple of inches is left between the edges of the facing and the edges of the board. The board 7 at its scores 8 and 9 and beyond the facing 11 is formed 70 with substantially V-shaped cut away portions 12, and the said board is further provided with transversely extending scores arranged at a direct right angle to the scores 8 and 9 and designated by the numerals 13 75 and 14. These scores 13 and 14 intersect the juncture of the walls provided by the V-shaped cut-away portions. The free edges of both the top and bottom of the device are also cut away as at 15 and 16, the longitudinal edges formed thereby being arranged at 80 a right angle to the scores 8 and 9, while the opposite edges provided by the cut away portions are inclined or beveled toward the inner faces of the said top and bottom. The 85 longitudinal edges of the top and bottom are scored as indicated by the numerals 17 and 18 respectively, and these scores are arranged to intersect the points of meeting of the edges of the board provided by the cut 90 away portions 15 and 16 and are parallel with the scores 8 and 9 as well as with the edges of the top and bottom. The portion of the top and bottom beyond their scores 17 and 18 are adapted to be bent inwardly to 95 receive the inturned or offset edges of the closure 2, as will be hereinafter set forth.

20 designates binding tapes. The tapes may also have their inner edges stitched through the board and the facing 11, as designated by the numeral 19, if desired. These tapes may be of any suitable material and are of a width sufficient to extend a suitable distance beyond the edges of the board 7. The inner faces of the said bindings are 105 adapted to be adhesively connected to the mucilaginous coating 10 upon the board 7.

When the parts are positioned as above described, the board is placed upon a bending machine and all of the parts are bent 110

upon their scores so as to provide a substantially cross sectionally U-shaped structure.

The ends 6 have their boards 21 of a size equaling the length of the side 3 and the 5 width of the top and bottom of the body. These boards 21 are also coated with a suitable adhesive substance 22, whereby outer facings 23 are secured thereto. These facings 23 are also preferably constructed of 10 fiber matting, as illustrated in the drawings, but as stated in connection with the facing 11, other material may be substituted if desired. The facing 23 is of a lesser length and breadth than the board 21 so as to 15 leave an adhesive surface upon each of the boards between the edges of the facing and the edges of the boards. The boards 21 are each formed with a longitudinal score 24 and the edges of the said boards are cut or 20 inclined inwardly from the said score, as indicated by the numerals 25'. Stitched to the boards 21 and facings 23, adjacent the scores 24 are binding tapes 25, the same being also secured by the adhesive substance 25 22, and the said tape projects a suitable distance beyond the edges of the board. The ends when thus assembled are placed in a bending machine and the portions beyond the scores are bent at right angles to the 30 ends proper. The adhesive substance upon the board 21 will engage the said lapped members while the extremities of the laps are also stitched to the sides 6 as indicated by the numeral 27. The laps may be more 35 firmly connected with the ends 6 by suitable tacks indicated by the numeral 28. The closed corners of the body, thus formed, are provided with caps 29, which materially reinforce the said body. The free, or disconnected edges of the top, bottom and ends are 40 now bent inwardly so that the free ends of the tapes may be brought to overlie and secure to the top edges of the indent portions a rectangular bail 30, which forms the 45 mouth of the body. The tapes are all provided with a suitable mucilaginous substance and adhesively connected with the upper inner faces of the body. When this is accomplished a lining 31, of any suitable 50 material is glued within the said body, thus affording a finish for the interior of the body of the case.

The closure 2 provides a rectangular board 32 having its entire face coated with 55 an adhesive material. This board, as well as the boards forming the body of the case is also constructed of some suitable strong material, such as heavy card-board or the like, and the said board has each of its corners cut at right angles, as designated by the numeral 33. The board 32 is provided with longitudinal scores 34 and transverse scores 35, each of said scores intersecting at 60 the juncture of the right angular walls 65 formed by the cut away corners of the board.

The portions of the board between the scores and the edges of the board are adapted to be bent to provide the offset edges 36 of the closure.

The numeral 37 designates the facing for 70 the closure. This facing may be constructed of any desired material and is of a rectangular shape but smaller than the board 32 so as to leave a space between the edges of the facing and those of the board when the 75 said facing is adhesively connected with the board.

The numerals 38 designate the tapes which are stitched through both the board and the facing a suitable distance beyond the 80 scores of the board. These tapes project a suitable distance beyond the edges of the board and have their inner faces engaged by the mucilaginous substance upon the board. The remainder of the tapes are adapted to 85 be connected with the offset edges and with the top of the closure through the medium of some suitable adhesive substance.

The closure is hingedly connected to the 90 bottom of the body while the top edge or lap of the said closure is provided with locking elements which co-act with component locking elements carried by the top of the body.

In Fig. 6 I have shown a detail of one of 95 the end members which is mainly constructed substantially similar to that heretofore set forth, but in which a single strip of tape is employed. The end section is provided with the longitudinal scores 39 and 100 transverse scores 40. The portion projecting beyond the scores 40 is formed with V-shaped slits or openings 41, the same terminating at the juncture of the scores 39 and 40. The tape 42 is adapted to be bent 105 inwardly when the members are folded upon their scores so as to provide gussets which serve as an additional reinforcement for the bent edges of the device.

Having thus fully described the invention, what I claim as new is:—

The herein described construction of suit case embodying a body portion and a closure therefor, said body comprising a side, a top, a bottom, and a pair of ends, the side, top and bottom being formed of a single board which is provided with longitudinal and transverse scores adjacent its edges, the board being further provided with substantially V-shaped cut away portions at the juncture of the scores, a coating of adhesive material upon the board, a facing secured by the adhesive material to the board, binding tapes overlapping the board and secured to the said board and case, the ends of 120 the case each comprising a board, said board having its face provided with an adhesive coating, a facing secured to the board by the adhesive material, an overlapping binding strip connected with the board and facing, 125 130

the board being longitudinally scored, the scores of the board providing the side, top and bottom being bent to provide laps, the end sections adapted to be connected with the laps, the upper scores of all of the boards being bent inwardly and their binding strips connected with a rectangular bail and adapted to have their free ends connected with the inside of the body, and a cover for the

body, all substantially as and for the purpose set forth.

In testimony whereof I affix my signature in presence of two witnesses.

FREDRICK A. SCHWARZROCK.
